UNITED STATES PATENT OFFICE.

PHILIPP LIVA, OF BROOKLYN, NEW YORK.

WIRE-BENDING MACHINE.

1,422,455.

Specification of Letters Patent. Patented July 11, 1922.

Application filed November 20, 1920. Serial No. 425,430.

To all whom it may concern:

Be it known that I, PHILIPP LIVA, a citizen of the United States, and resident of Brooklyn, in the county of Kings and State 5 of New York, have invented certain new and useful Improvements in Wire-Bending Machines, of which the following is a specification.

This invention relates to improvement in 10 wire bending and cutting machine.

An object of this invention is to provide an effective, efficient and inexpensive device for bending and cutting wire to a shape and size to be used as so-called hair pins for interior 15 decorating work or in conjunction with construction work in general.

Other objects of this invention are to provide in such a device a means to receive the wire to be bent, adjustable means for limiting 20 the length of such wire and means for cutting same after part of the bending process has been gone through.

Further objects of this invention are to provide in such a device a lever pivoted to 25 connect to a platform and adapted to move in a horizontal plane, said lever being provided with a female bending die; an adjustable male bending die, the male and female dies being so disposed relative to each other 30 that when said lever is swung to a position at right angles to its original inoperative position, the wire is curved so as to form two equal and parallel legs when cut, and means for limiting the travel of said lever.

Still further objects of this invention are 35 to provide another lever mounted on said platform adapted to swing in a vertical plane and provided with a bending member so disposed as to bend a portion of the now 40 formed parallel legs of the wire, downwardly, and means for limiting its downward travel.

A still further object of this invention is 45 to provide a device which by making suitable and convenient changes may be used for similar purposes.

The above and further objects in view will 50 more fully be understood from the following description together with the accompanying drawings forming part of this specification and in which,

Figure 1 is a plan view of my invention.

Figure 2 is a cross sectional elevation of same taken on line 2-2 of Figure 1.

55 Figure 3 is a cross sectional view of same taken on line 3-3 of Figure 1, showing in

dotted lines, the downward position of the bending and cutting lever operating in a vertical plane.

Figure 4 is a perspective view of the bending lever showing the female die upon the under-surface thereof.

Figure 5 is a perspective view of a preferred form of an adjustable male die.

Figure 6 is a perspective view of a preferred form of an adjustable stop member.

Figure 7 shows a product of my device.

The drawings disclose a preferred embodiment of my invention having a platform or base 1 made from suitable material.

Base 1 has formed thereon and made integral therewith, the transverse parallel wall-like projections or uprights 2 and 3, and the longitudinal wall-like projection or upright 4, the latter joining with the rear 75 ends of the former.

Base 1 is provided with an opening 4' between uprights 2 and 3. Uprights 2 and 3 are bored to receive a bolt 5 upon which is mounted a lever 6. This lever is adapted 80 to travel in a vertical plane and has formed thereon a protrusion 7 for limiting its downward position.

Secured to the sides of lever 6 by suitable means are bender 8 and knife or cutter 9, 85 the former being connected to the inner side and the latter to the outer side thereof extending slightly lower than the former.

Secured to the lower end of upright 2 in a slot is a cutting plate 10 made from suitable material, and directly above this plate there is formed an aperture 11 through which a wire may be drawn to be bent and cut. A bender plate 11' is inserted and secured in a slot provided in base 1 directly 90 abreast of bender 8 when the latter is in downward position. Lever 6 is disposed between uprights 2 and 3 so that there exists between bender 8 and bender plate 11' sufficient space in order to give play to the 100 bending wire and so that knife or cutter 9 contacts with cutting plate 10 when lever 6 is in extreme downward position, as will more fully be explained below.

Pivotedly connected to base 1 by suitable 105 means 12 is a lever or bending member 13, adapted to travel in a horizontal plane, being provided at its under-surface with an arcuated female bending die 14, disposed at about its center, and a boss 15, said lever being provided with a suitable handle 15'.

An adjustable male bending or forming

die 16, slotted at 17 to receive an adjusting bolt 18 for securing it in grooved portion 19 of base 1, is provided with a curved portion 20 for bending a wire as will be explained below. Lever 13 is cut out at 21 to clear bolt 18.

Lever 13 is prevented from going too far back by upright 4. When moved in the direction of the operator it is held fixed in 10 extreme position by clamping member 21' secured to base 1. This clamping member is disposed at a suitable distance from the pivoted point of lever 13 and on a line at right angles to the inoperative position of 15 the latter, so that when lever 13 is in clamping position, it is at right angles to its inoperative position, the engaging portion of die 14 being in juxtaposition to adjustable die 16.

20 An adjustable wire stop 22 having an upright portion 23 is slotted at 24 to receive an adjusting bolt 25 for securing it in grooved portion 26 of base 1.

The wire is bent to the desired shape as 25 follows: Adjustable stop 22 is adjusted and clamped in position by bolt 25, until the distance between upright portion 23 and cutting plate 10 is equal to the desired length of wire to be bent. Wire 27, which 30 is usually coiled on a spool, is drawn through aperture 11 to the inner end of adjustable stop 22, the wire passing alongside adjustable male die 16, as clearly shown in Figures 1 and 2. Lever 13 carrying fe- 35 male die 14 is then moved towards the wire and during the course of its motion carries the wire with it, the latter engaging male die 16. During this operation female die 14 cooperates with male die 16 in such manner that the wire is bent around curved 40 portion 20 of the latter in a hook shape and forms a leg 28 parallel to the first portion 29 of the wire when lever 13 reaches clamp 21'. The position now occupied by lever 45 13 and female die 14 is shown by dotted lines in Figure 1. By means of clamp 21', lever 13 is held in fixed downward position so that the curved portion of the wire is held immovable thereunder during the following operations.

Lever 6 is now drawn downward and due 50 to knife or cutter 9 being slightly lower than bender 8, the wire is first cut so that two equal parallel legs 28 and 30 of the hook shape are produced and then as lever 6 is moved further downward until protrusion 7 engages base 1, the parallel legs of the hook are bent downwardly by bender 8.

By way of these operations, so-called hair 60 pins, as shown in Figure 7, are produced.

To extract these now formed hair pins, lever 6 is raised and the pin released by swinging lever 13 to backward position as shown in full lines, Figure 1.

65 In conjunction with my device, a spring

means not shown, may be attached below the curved portion of the hair pin for lifting the latter over male die 16 and causing it to fall through opening 4' into a container conveniently placed thereunder.

70

These hair pins may be made of any desired length, within limitations of the size of the machine which may of course be varied, by adjusting stop 22. It is to be observed that male die 16 should be adjusted correspondingly, so that a line drawn tangentially from the highest point of curved portion 20 divides the portion of the wire to be bent equally.

These hair pins so formed may be used for 80 interior decorating work and in conjunction with construction work in general. Wire netting, expanded metal or the like may be attached which is subsequently covered with plaster or similar building material.

My device is not limited to producing the particular shape of pins described above, for by changing the dies and other bending parts it may be adapted for any similar pose.

90

Be it understood that I shall not be limited to the particular form, shape or other construction described above, and I, therefore, reserve for myself the right to make 95 alterations and changes in and to my device and amendments thereto, consistent with my ideal and within its purview, I claim:

1. A wire bending and cutting device 100 comprising in combination a base, a bending member pivotally connected to said base adapted to swing in horizontal direction, said bending member being provided at its under-surface with an arcuated die, a lever 105 swingably mounted on said base provided at its outer end with a cutter and at its inner end with a bender, said lever being adapted to swing in a vertical direction, an aperture formed in said base near the cutter end of said lever adapted to receive a wire 110 to be bent, an adjustable stop member secured to said base and disposed opposite said aperture, a stationary clamping member secured to said base adapted to hold said bending member in a fixed position during the subsequent operation of said lever, and an adjustable die secured to said base near 115 said lever and disposed on a line with said aperture.

120

2. A wire bending and cutting device comprising in combination a platform, a bending member swingably connected to said platform adapted to operate in a horizontal plane, said bending member being 125 provided at its under-surface and at about its center with a curved projection, a stationary clamping member secured to said platform in a position at right angles to the normal and inoperative position of said 130

- bending member, a lever member swingably mounted on said platform adapted to operate in a vertical plane, a cutter secured at the lower outer end and a bender secured at the lower inner end of said lever member, an aperture formed in said platform near the cutter end of said lever adapted to receive a wire to be bent, a wire-stop member adjustably secured to said platform and disposed opposite said aperture adapted to limit the length of the wire, and a combination guide and die adjustably secured to said platform near said lever member and on a line with said aperture.
3. A new article of manufacture for bending wire comprising in combination a base provided at one end with a lever swingably mounted thereon, the latter being adapted to operate in a vertical plane, and a bending member pivotally connected thereto adapted to operate in a horizontal plane, said bending member having an arcuated die secured at its under-surface, a bender secured at the inner side of said lever, a cutter secured at the outer side of said lever, an aperture formed in a projection extending from said base at the end nearest said cutter adapted to receive a wire, an adjustable stop secured at the end of said base opposite said aperture, adapted to limit the length of the wire, a combination adjustable guide and die secured to said base having one of its sides alined with said aperture, and a stationary clamp secured to said base, and adapted to hold said former level in desired position.
4. A new article of manufacture for bending and cutting wire comprising in combination a base provided at one end with two wall-like projections spaced apart and having an opening thereinbetween, a lever swingably mounted between said wall-like projections, a bender secured at one side of said lever and a cutter secured at the other side of said lever, a cutting plate secured to one of said wall-like projections adapted to contact with said cutter when said lever is in downward position, an aperture formed directly above said cutting plate adapted to receive a wire to be bent and cut, a bending member pivotally secured to said base adapted to swing in a horizontal plane, means for clamping said bending member, means for limiting the length of the wire to be bent, and means for forming the curved portion of the wire.
5. An article for bending and cutting wire comprising in combination a platform having two parallel uprights made integral therewith and forming a receiver for a lever, a lever provided with an inner bending side and an outer cutting side swingably mounted between said uprights, a cutting plate secured to one of said upright extensions adapted to contact with the cutting side of
- said lever when the latter is in downward position, an aperture formed directly above said cutting plate adapted to receive a wire to be bent and cut, adjustable means for limiting the length of the wire, when so received, and adjustable means for forming a curved bend in the wire.
6. In a wire bending and cutting device provided with a platform the combination of a combined knife and bender lever swingably mounted on said platform, a cutting plate disposed on said platform in such manner as to contact with the knife portion of said lever when the latter is in downward operative position, means for receiving, and adjustable means for limiting the length of a wire to be bent and cut, means for curving the wire so as to form two equal and parallel legs, said latter means comprising an adjustable male die secured to said platform, a bending member pivotally connected to said platform and provided at its under-surface with a female die, and means for clamping said bending member in parallel relation to said platform while the wire legs are being bent and the wire cut.
7. In a wire bending device provided with a platform and means for receiving a wire to be bent and cut, a lever mounted on said platform adapted to swing in a vertical plane, another lever pivotally connected to said platform adapted to swing in a horizontal plane, said former lever being provided with a knife and bender member, said latter lever being provided with a female die, an adjustable male die disposed on said platform in such manner that when said latter lever is in its extreme operative position said male and female dies are in juxtaposition with one leg of the wire which is now curved, between them.
8. In a wire bending device provided with a platform, means for receiving a wire to be bent, means for limiting the length of such wire, and means for cutting same, a lever pivotally connected to said platform adapted to move in a horizontal plane, said lever being provided with a female bending die, an adjustable male bending die secured to said platform, said male and female dies being so disposed relative to each other that when said lever is swung to a position at right angles to its original inoperative position, the wire is curved so as to form two equal and parallel legs when cut, and another lever mounted on said platform adapted to swing in a vertical plane, said latter lever being provided with a bending member so disposed as to bend a portion of the now formed parallel legs downwardly and means for limiting its downward travel.
9. In a bending device of the character described, a lever provided with a bending side and a cutting side, and adapted to travel in a vertical plane, another lever provided

with an arcuated female bending die and adapted to travel in a horizontal plane, and an adjustable male bending die disposed so as to cooperate with said female bending die when desired.

10. In a wire bending and cutting device, a combination cutter and bender-lever adapted to operate in a vertical plane, a bender lever adapted to operate in a horizontal plane, an adjustable forming die disposed so as to cooperate with said bender-lever, and means for limiting the downward motion of said combination lever.

11. In a bending and cutting device means for bending the end of a continuous wire first in a horizontal plane so as to form a hook with two parallel legs, means for severing one of the hook legs from the wire and

simultaneously bending a portion of the legs of the hook in a vertical plane.

12. In a bending and cutting device a horizontally operable shaping member, an adjustable die member co-operating with said shaping member and a vertically operable combination severing and bending member, said shaping member adapted to form at the end of a continuous wire a U-shaped hook having parallel legs, said severing and bending member adapted to separate the hook portion from said wire and bend the legs of the hook.

Signed at New York, in the county of New York and State of New York, this 1st day of November A. D. 1920.

PHILIPP LIVA.
